UNITED STATES PATENT OFFICE.

GEORGE P. WIGGINTON, OF KALAMAZOO, MICHIGAN, ASSIGNOR TO KALAMAZOO LOOSE LEAF BINDER CO., OF KALAMAZOO, MICHIGAN.

TEMPORARY BINDER OR LOOSE-SHEET HOLDER.

1,093,370.

Specification of Letters Patent. Patented Apr. 14, 1914.

Application filed September 22, 1913. Serial No. 791,181.

To all whom it may concern:

Be it known that I, GEORGE P. WIGGINTON, a citizen of the United States, residing at Kalamazoo, Michigan, have invented certain new and useful Improvements in Temporary Binders or Loose-Sheet Holders, of which the following is a specification.

This invention relates to improvements in temporary binders or loose sheet holders.

10 My improvements relate particularly to the adjusting mechanism.

I have specially designed my improvements for use in temporary binders or loose sheet holders of the type in which binding strips extend between the covers, such as is shown in United States Letters Patent to Bushong, No. 851,276, issued April 23, 1907. My improvements may however, be readily adapted to binders considerably modified

20 in general structure.

The main objects of this invention are: First, to provide in a temporary binder or loose sheet holder an improved adjusting mechanism, by means of which the binders 25 may be quickly and easily adjusted to permit insertion or removal of sheets, or to lock the sheets within the binder. Second, to provide an improved temporary binder or loose sheet holder having these features, 30 which may be adjusted from the outside of the cover containing the adjusting mechanism. Third, to provide in an improved temporary binder or loose sheet holder an adjusting mechanism which is simple and economical in structure and very simple and 35 convenient in operation.

Further objects, and objects relating to structural details, will definitely appear from the detailed description to follow.

40 I accomplish the objects of my invention by the devices and means described in the following specification.

The invention is clearly defined and pointed out in the claims.

45 A structure which is a preferred embodiment of my invention is clearly illustrated in the accompanying drawing forming a part of this specification, in which:

Figure I is a detail outside view of a 50 structure embodying the features of my invention with the covers extended, the outer walls of the covers and also the flexible back strip or back piece being omitted. Fig.

II is a detail central section of a complete binder on a line corresponding to line 2-2 of Fig. I with the covers closed, sheets being shown in conventional form in the binder. Fig. III is a detail section on a line corresponding to line 3-3 of Fig. I, showing details of the adjusting mechanism. Fig. IV is a detail section on a line corresponding to line 4-4 of Fig. I, showing the details of the cross bar or head and its guides. Fig. V is a detail outside view corresponding to that of Fig. I of a modified structure embodying the features of my invention, the outer walls of the cover being omitted. Fig. VI is a detail section on a line corresponding to line 6-6 of Fig. V. Fig. VII is a detail outside view of another modification embodying the features of my invention, the outer walls of the covers being omitted. Fig. VIII is a detail section on a line corresponding to line 8-8 of Fig. VII.

In the drawing similar reference characters refer to similar parts throughout the several views, and the sectional views are taken looking in the direction of the little arrows at the ends of the section lines.

Referring to the drawing the covers are 80 designated generally by the numerals 1 and 2. These covers preferably consist of rectangular frames 3 having inner walls 4, and outer walls 5, secured thereto providing chambers within the covers.

The frames are preferably of wood and the inner and outer walls are preferably of sheet metal.

The outer walls are faced with a suitable binding 6 of cloth or leather, while the inner walls are faced with paper or other suitable covering as 7.

The structure illustrated is provided with clamping or binding bars 8 pivotally mounted on hinges 9 projecting from the ends of the covers. As these clamping or binding bars form no part of my present invention they are not described with further detail herein.

The binding strips 10 extend between the 100 covers and are connected to the cover 2 at 11, the other ends of the binding strips are connected to the adjustable member or cross bar 12 at 13. The cross bar or cross head 12 is arranged within the chamber of the cover 105 1 to be adjusted longitudinally therein, and

is provided with guide rollers 14 engaging longitudinal slots 15 in the inner wall of the cover, so that the cross bar or cross head is guided in its reciprocating movement. See 5 Fig. IV. When the cross bar is moved toward the inner end of the cover 1 the binding strips are extended to loosen the binder, and when moved in the opposite direction they are retracted to tighten the binder 10 upon the sheets or leaves.

The cross bar 12 is provided with a central outwardly projecting arm 16 carrying a roller 17 which engages the cam groove 18 in the cam actuating member 19, the cam 15 groove being in the outer side or face of the member, that is, the side toward the outer wall of the cover. The cam groove is in the form of a spiral. This cam actuating member 19 in the structure shown in Figs. I, II 20 and III is a worm gear, it being provided with peripheral worm teeth 20.

The actuating member gear is journaled at 21 on the inner and outer walls of the cover. The actuating worm 22 is supported 25 by suitable bearing brackets 23 in engagement with the teeth of the actuating member 19. The shaft of the worm 24 is extended to the edge of the cover and adapted to receive a key by means of which it may 30 be rotated from the outside of the cover, the cover being provided with a hole 25 adapted to receive the key. By this arrangement of parts I provide a device which is self locking, that is, it remains in its adjusted 35 position without other locking means, the worm 22 engaging the teeth of the actuating member constituting a lock and further, the spiral form of the cam, it being of comparatively low pitch, tends to keep the parts in 40 their adjusted position.

The guides for the member 12 are preferably so arranged relative to the axis of the cam and the cam engaging part engages the cam so that the strain is radial to its 45 axis.

In the modification shown in Fig. V the journal 26 of the adjusting member 27 has an opening 28 adapted to receive a key either at its inner or outer ends. To increase the power for tightening the binder 50 when desired I provide a pinion 29 which meshes with the teeth of the adjusting member 27, the pinion being provided with a key hole 30 of the same size as the key hole 55 28, so that the key may be used in either place.

In the modification shown in Figs. VII and VIII the member 31 is provided with quite an abrupt cam groove 32 which extends in the arc of a circle from a point near the journal 33 of the adjusting member to a point near its periphery. More power is required for operating this embodiment of my invention than that shown in Fig. I, but 65 the actuating worm 22 provides sufficient

power so that the binder may be quickly and easily adjusted. It is, as stated, more rapid in its operation than the embodiment shown in Fig. I. The form shown in Fig. V also has the advantage of being more rapid in its 70 operation than that shown in Fig. I. Each form has its advantages in certain sizes of binders or binders designed for certain purposes.

I contemplate other modifications and 75 adaptations than that shown, but have not illustrated the same as I believe the embodiments shown will enable those skilled in the art to which my invention relates to adapt or embody the same as may be desired. 80

The flexible back piece or back strip 34 telescopes into the covers and is connected to the cross head or adjustable member 12 of one cover and to the springs 35 in the other cover. The action of the back strip is 85 fully pointed out in the Bushong patent hereinbefore referred to.

Having thus described my invention, what I claim as new and desire to secure by Letters Patent is:

1. The combination with the covers, one of said covers having a chamber therein, binding strips extending between said covers, a cross bar to which said binding strips are connected arranged in said chamber, the other ends of said binding strips being connected to the other cover, guides for said cross bar, said cross bar having a central outwardly projecting arm thereon provided with a roller, a worm gear having a 100 spiral cam groove on its face with which the roller on said cross bar arm is engaged, and an actuating worm for said gear.

2. The combination with the covers, one of said covers having a chamber therein, 105 binding strips extending between said covers, a cross bar to which said binding strips are connected arranged in said chamber, the other ends of said binding strips being connected to the other cover, guides for 110 said cross bar, said cross bar having a central outwardly projecting arm thereon provided with a roller, a worm gear having a cam groove on its face with which the roller on said cross bar arm is engaged, and an actuating worm for said gear.

3. The combination with the covers, one of said covers having a chamber therein, binding strips extending between said covers, a cross bar to which said binding strips are connected arranged in said chamber, the other end of said binding strips being connected to the other cover, guides for said cross bar, said cross bar being provided with a roller, and a rotatable actuating member 120 provided with a spiral cam with which the roller on said cross bar engages.

4. The combination with the covers, one of said covers having a chamber therein, binding strips extending between said covers, a 130

cross bar to which said binding strips are connected arranged in said chamber, the other end of said binding strips being connected to the other cover, guides for said cross bar, said cross bar being provided with a roller, and a rotatable actuating member provided with a cam with which said cross bar engages.

5. The combination with the covers, one of said covers having a chamber therein, a binding strip extended between said covers, an adjustable member to which said binding strip is connected arranged in said chamber, the other end of said binding strip being connected to the other cover, a worm gear provided with a spiral cam operatively associated with said adjustable member to adjust the same as the gear is rotated, and an actuating worm for said gear.

10. 6. The combination with the covers, one of said covers having a chamber therein, a binding strip extended between said covers, an adjustable member to which said binding strip is connected arranged in said chamber, 15 the other end of said binding strip being connected to the other cover, a worm gear provided with a cam operatively associated with said adjustable member to adjust the same as the gear is rotated, and an actuating 20 worm for said gear.

7. The combination with the covers, one of said covers having a chamber therein, a binding strip extended between said covers, an adjustable member to which said binding strip is connected arranged in said chamber, the other end of said binding strip being connected to the other cover, a gear provided with a spiral cam operatively associated with said adjustable member to adjust the same as the gear is rotated, and means for 30 rotating said gear.

8. The combination with the covers, one of said covers having a chamber therein, a binding strip extended between said covers, an adjustable member to which said binding strip is connected arranged in said chamber, the other end of said binding strip being connected to the other cover, a gear provided with a cam operatively associated with said 45 adjustable member to adjust the same as the gear is rotated, and means for rotating said gear.

9. The combination with the covers, one of said covers having a chamber therein, a binding strip extending between said covers, an adjustable member to which said binding strip is connected arranged in said chamber, the other end of said binding strip being connected to the other cover, and a rotatable member provided with a spiral cam 55 acting on said adjustable member to adjust the same as the cam member is rotated.

10. The combination with the covers, a binding strip extending between said covers 60 and connected to one of them, a worm gear

having a spiral cam on its face mounted on the other cover, an adjustable member to which said binding strip is connected provided with a cam engaging part, and an actuating worm for said gear.

11. The combination with the covers, a binding strip extending between said covers and connected to one of them, a worm gear having a cam on its face, mounted on the other cover, an adjustable member to which 70 said binding strip is connected provided with a cam engaging part, and an actuating worm for said gear.

12. The combination with the covers, a binding strip extending between said covers 75 and connected to one of them, a gear provided with a spiral cam mounted on the other cover, an adjustable member to which said binding strip is connected provided with a cam engaging part, and means for 80 driving said gear.

13. The combination with the covers, a binding strip extending between said covers and connected to one of them, a gear provided with a cam mounted on the other 90 cover, an adjustable member to which said binding strip is connected provided with a cam engaging part, and means for driving said gear.

14. The combination with the covers, a binding strip extended between said covers and connected to one of them, an adjustable member to which said binding strip is connected, and a rotatable member carried by the other cover and provided with a spiral 95 cam operatively associated with said adjustable member to adjust the same as the cam member is rotated.

15. In a temporary binder the combination with the covers and an adjusting mechanism comprising a worm gear having a spiral cam groove on its face, an adjustable member provided with a cam engaging part, and an actuating worm for said gear.

16. In a temporary binder the combination with the covers and a binder adjusting mechanism comprising a worm gear having a cam groove on its face, an adjustable member provided with a cam engaging part, and an actuating worm for said gear.

17. In a temporary binder the combination with the covers and a binder adjusting mechanism comprising a gear provided with a cam carried by one of said covers, an adjustable member actuated by said cam connected to the other of said covers, and means for driving said gear.

18. In a temporary binder the combination with the covers and a binder adjusting mechanism comprising an adjustable member connected to one of said covers, and a rotatable cam member having a spiral cam operatively associated with said adjustable member and carried by the other cover.

19. In a temporary binder the combination

tion with the covers and a binder adjusting mechanism comprising an adjustable member, and a rotatable cam member, said adjustable member being provided with a roller engaging said cam member and with suitable guides.

20. In a temporary binder, the combination with the covers, a binding strip extending between said covers and connected to one of them, a gear provided with a cam carried by the other cover, an adjustable member actuated by said cam connected to said binding strip, and a screw means for actuating said gear and retaining it in its adjusted positions.

21. In a temporary binder, the combination with the covers, a binding strip extending between said covers and connected to one of them, a gear provided with a cam carried by the other cover, an adjustable member actuated by said cam connected to said binding strip, and means for actuating said gear and automatically retaining it in its adjusted positions.

22. In a temporary binder, the combination with the covers, binding strips extending between said covers and connected to one of them, a cam member carried by the other cover, an adjustable member actuated by said cam member connected to said binding strips, and a screw means for actuating said cam member and retaining it in its adjusted positions.

23. In a temporary binder, the combination with the covers, of a binder adjusting mechanism comprising a gear provided with a cam, and a screw means for actuating said gear whereby the gear is retained in its adjusted positions.

24. In a temporary binder, the combination with the covers and a binder adjusting means comprising an adjustable member connected to one of said covers and a rotatable cam member having a spiral cam operatively associated with said adjustable member and carried by the other cover, and a screw means for actuating said cam mem-

ber and whereby it is retained in its adjusted positions.

25. In a temporary binder, the combination with the covers, of binding strips extending between said covers and connected to one of them, a rotatable cam member having a spiral cam on its face carried by the other cover, an adjustable member connected to said binding strips and having a part engaging said cam, and a guide for said adjustable member arranged so that the stress on the cam is radial to its axis.

26. In a temporary binder, the combination with the covers, of binding strips extending between said covers and connected to one of them, a rotatable cam member carried by the other cover, an adjustable member connected to said binding strips and having a part engaging said cam, and a guide for said adjustable member arranged so that the stress on the cam is radial to its axis.

27. In a temporary binder, the combination with the covers, of binding strips extending between said covers and connected to one of them, a rotatable cam member having a spiral cam on its face carried by the other cover, and an adjustable member connected to said binding strips and having a part engaging said cam so that the stress on the cam is radial to its axis.

28. In a temporary binder, the combination with the covers, of binding strips extending between said covers and connected to one of them, a rotatable cam member carried by the other cover, and an adjustable member connected to said binding strips and having a part engaging said cam so that the stress on the cam is radial to its axis.

In witness whereof, I have hereunto set my hand and seal in the presence of two witnesses.

GEORGE P. WIGGINTON. [L.S.]
